UNITED STATES PATENT OFFICE.

KOBY KOHN, OF NEW YORK, N. Y.

TOY TORPEDO.

Application filed October 6, 1926. Serial No. 139,922.

This invention relates to toy torpedoes and more particularly to what may be termed safety toy torpedoes.

It is a general object of the present invention to provide a novel and improved form of safety toy torpedo.

More particularly it is an object of the invention to provide a toy torpedo in which the container, for the explosive, is formed of a material which is deformable upon the impact resulting from throwing the torpedo against a hard surface and in which at least one deformable wall is provided with an abrasive surface adapted to ignite the explosive only on impact.

A further object of the invention consists in the provision of a toy torpedo in which the deformable walls of the explosive container are spaced apart and provided with abrasive coatings adapted to be brought together to ignite the explosive only upon sufficient impact to deform one or more of the walls.

A still further object of the invention consists in the provision, in a toy torpedo, of opposing deformable walls containing between them an explosive composition, the usual abrasive for exploding the composition being secured to the aforementioned walls, whereby it can only be moved when said walls are deformed.

As usually constructed, toy torpedoes comprise a container for the explosive and abrasive material formed of any suitable substance such as paper, cardboard, clay, or the like. In a compartment in the container is placed the powdered explosive composition and granular material such as gravel, which materials are then sealed into the compartment. The torpedo is adapted to be exploded when the granular material abrades the explosive material to ignite the same. Such abrasion may take place unintentionally during shipping and handling of the torpedoes, which renders them extremely unsafe and unsatisfactory for manufacture and shipment in large quantities. The present invention contemplates the provision of an improved torpedo in which the abrasive is permanently secured to the walls of the container and particles thereof can only come in contact with each other to ignite the explosive upon considerable deformation of the walls of the container whereby explosion takes place only upon intentional impact.

In the accompanying drawings and following specification there are disclosed two exemplary embodiments of the present invention, but it is to be understood that various changes may be made therein without departing from the spirit of the invention or the scope of the appended claims.

In said drawings:

Figure 1 is a perspective view of a semi-spherical type of torpedo;

Figure 2 is a sectional view taken on a plane passing thru the axis of the torpedo;

Figure 3 is a central longitudinal section thru a tube type of torpedo; and

Figure 4 is a transverse section on line 4—4 of Figure 3.

Referring to the drawings, there is disclosed in Figures 1 and 2 a novel form of torpedo in which the container for the explosive material is formed from two sheets of cardboard or like resilient and deformable material which is non-frangible. The outer of the two parts of the container is shown at 10 and comprises a substantially semi-spherical cup-like portion formed of the aforementioned material. To close the open end of this cup, a second cup-like portion 11 is provided. The curvature of its bottom may be of slightly less radius than that of the cup 10, but is substantially concentric therewith, whereby the two cups may be telescoped or nested as shown in Figure 2 to leave a space or compartment 12 between the same adapted to receive the explosive composition indicated in small dots in the drawing. The upper or outer walls of the cups 10 and 11 become substantially cylindrical so that they telescope as best shown at 13 and may be securely fastened together by the use of suitable adhesive. Preferably the cup 11 has its wall turned downwardly and over the outer surface of the cylindrical portion of the cup 10 as shown at 14 to provide a more rigid structure and a greater surface between the cups 10 and 11 to receive adhesive, whereby a gas tight container is provided.

It will be noted that there are but two walls to the compartment 12, one concave and the other convex, it being thereby best suited to resist the expending gases resulting from an explosion so that a louder report will be given. The inner surfaces of the walls of the compartment 12 are each coated with a suitable abrasive such as sand, finely

granulated gravel, emery, or the like. This may be secured to the respective surfaces by a suitable adhesive before the torpedo is assembled.

- 5 In assembling the torpedo, each of the cups 10 and 11 is first formed complete with its layer of abrasive material 15. A suitable quantity of explosive material is placed in the cup 10. This material may comprise an 10 intimate, mechanical mixture of powdered chlorate of potash, sulfur and antimony, or any other suitable explosive composition. The cup 11 is then placed in position and secured by a suitable adhesive between the 15 contiguous surfaces of the two cups.

If desired, the thus completed torpedo may be dipped into a suitable solution which, when dry or cold will harden on the surface and increase the gas tight qualities of the 20 torpedo. This solution may also be used to render the torpedo moisture proof. It deposits a layer or coating 16 on the exterior surface and effectively seals the torpedo and increases the resiliency of the cups. Certain 25 types of glue are very effective for the above purpose.

By referring to Figure 2 it will be seen that the walls of the cups 10 and 11 are spaced apart and between these abrasive surfaced walls is arranged the explosive compound. When the torpedo is thrown against a hard surface the impact will be sufficient to deform at least one of the walls and cause it to come into contact with the other or opposing wall whereby the abrasive surfaces are rubbed together and ignite the explosive composition contained between them. The material forming the cups is such that it may only be deformed by considerable impact, 40 and since all of the abrasive material is stationary under normal circumstances, there is no danger of a premature explosion except upon the occurrence of an extremely violent impact, which is highly improbable during 45 the manufacture and shipping of the torpedo.

If it is desired that the torpedo be tubular in form to conform to the present style, it may be constructed as shown in Figures 3 and 4. Here the outer cup 17 is tubular in form with the flat bottom 18. Concentrically inside of the cup 17 is arranged a similar shaped but smaller sized cup 19 having a flat circular bottom 20. This cup 19 is secured in the flat bottom 21 of a larger cup 22 whose outside dimensions are the same as those of the cup 17. The two cups 19 and 17 are held together by a cylindrical tube 23 which snugly engages the walls 17 and 22 and is secured thereto by a suitable adhesive or merely by friction. The inner walls of the cup 17 and the outer walls of the cup 19 are covered with a suitable abrasive 24, as described in connection with the preferred 60 form. Before assembling, the explosive ma-

terial 25 is placed in the cup 17. After assembly is complete, the outer coating 26 of gas tight material may be applied as described in connection with the previous modification.

70

It will be seen that in this form as in the previous one, the explosive material is arranged between opposing walls covered with abrasive and slightly spaced apart so that upon deformation of either of the walls, two 75 abrasive surfaces are brought together to ignite the explosive, but that under normal conditions these two abrasive surfaces are rigidly held apart by the normal resilience 80 of the material comprising the container so that accidental explosion can not take place.

80

Having thus described the invention the claims to be considered are:

1. In a toy torpedo, in combination, a container having a pair of walls substantially 85 parallel to each other and close together, abrasive on said walls and explosive material between the walls, said walls being made of material deformable on impact.

90

2. In a toy torpedo, in combination, a 95 container for explosive having a pair of walls normally maintained a short distance apart, said walls being formed of bendable material and having their facing surfaces abrasive, and explosive material between said abrasive surfaces, one of said walls being adapted to be deformed upon impact to ignite the explosive by abrasion.

95

3. In a toy torpedo, in combination, a container for explosive formed with two bendable opposed walls separated only by a thin 100 layer of said explosive, the facing surfaces of said walls being abrasive.

100

4. A toy torpedo comprising a pair of 105 substantially concentric walls of bendable material having between them an explosive compound, the inner surface of one of said walls being abrasive.

105

5. In a toy torpedo, in combination, a 110 cup-like container, explosive compound therein and a cup-like closure for said container, the open sides of both cups facing in the same direction, one of the walls in contact with said explosive being bendable under the impact caused by throwing said 115 torpedo against a hard surface.

115

6. In a toy torpedo, in combination, a 120 cup-like container, an explosive therein and a nested cup-like closure for said container, one of the surfaces in contact with said explosive being abrasive.

120

7. In a toy torpedo, in combination, a 125 cup-like container, an explosive therein and a nested cup-like closure for said container, one of the surfaces in contact with said explosive being abrasive, and one of the walls in contact with said explosive being deformable under the impact caused by throwing said torpedo against a hard surface.

125

8. In a toy torpedo, in combination, de- 130

formable, gas-tight walls having confronting abrasive surfaces, explosive between said surfaces and means whereby said surfaces may be brought into engagement by the impact of said torpedo on a hard surface while said walls remain gas-tight.

9. In a toy torpedo, in combination, curved bendable, confronting walls having abrasive facing surfaces and explosive between said surfaces adapted to be ignited when said surfaces are brought into engagement by deformation of said walls.

10. A torpedo containing explosive and abrasive, said abrasive being securely mounted on a surface which is bendable while remaining gas-tight.

11. In a toy torpedo, in combination, an explosive composition positioned between two surfaces relatively movable toward each other, upon impact, due to the bendable quality of one of said surfaces.

12. In a toy torpedo, in combination, an explosive composition positioned between relatively movable surfaces one of which is

bendable upon the impact of the torpedo against a hard surface.

13. In a toy torpedo, in combination, an explosive composition positioned between relatively movable surfaces one of which is bendable upon the impact of the torpedo against a hard surface, one of said surfaces being abrasive.

14. In a toy torpedo, in combination, an explosive composition loosely positioned between relatively movable surfaces secured together, one of said surfaces being bendable upon the impact of said torpedo against a hard surface.

15. In a toy torpedo, in combination, an explosive composition loosely positioned between relatively movable surfaces secured together, one of said surfaces being bendable upon the impact of said torpedo against a hard surface, and at least one of said surfaces being abrasive.

In testimony whereof I hereunto affix my signature.

KOBY KOHN.
